UNITED STATES PATENT OFFICE.

JOHN FAULDS, OF OAK PARK, ILLINOIS, ASSIGNOR OF ONE-HALF TO JOHN I. MARSHALL, OF CHICAGO, ILLINOIS.

BAKE-OVEN.

1,018,178.

Specification of Letters Patent.

Patented Feb. 20, 1912.

Application filed June 10, 1909. Serial No. 501,268.

To all whom it may concern:

Be it known that I, JOHN FAULDS, a subject of the Kingdom of Great Britain, and resident of Oak Park, county of Cook, and 5 State of Illinois, have invented certain new and useful Improvements in Bake-Ovens, of which the following is a specification and which are illustrated in the accompanying drawings, forming a part thereof.

10 The invention relates to bakers' ovens, and more particularly to those of the type termed portable ovens wherein the walls of the oven structure are constructed in detachable sections adapted to be fitted together at 15 the place of use.

A detail of the invention provides, also, for constructing the oven in sizes of differing capacity through the use of sections providing additional baking compartments 20 which may or may not be incorporated in the oven structure as desired.

The object of the invention is to provide a baker's oven of improved construction; and the invention is exemplified in the apparatus 25 to be hereinafter described and illustrated in the accompanying drawings, in which—

Figure 1 shows in front elevation a baker's oven embodying the features of the invention; Fig. 2 is a central vertical longitudinal 30 sectional view of the same; Fig. 3 is a vertical cross-sectional view of the oven taken on the line 3—3 of Fig. 2; Fig. 4 is a plan sectional view taken on the broken line 4—4 of Fig. 3; Fig. 5 is similar to Fig. 3 but shows 35 an oven of smaller size constructed by omitting certain parts included in the arrangement illustrated in Figs. 1 to 4 inclusive; and Fig. 6 is a sectional plan view taken on line 6—6 of Fig. 3.

40 The oven provided by the invention preferably assumes the form of a rectangular chambered casing, generally designated by the numeral 10 in the accompanying drawings. In order that this structure may be 45 portable the walls of the casing are preferably made sectional, the floor and cover members, designated 11 and 12, respectively, being, as shown, each constructed in the form of a single slab. The vertical walls of 50 the structure, as the ends 13, 14, and the sides 15, 16, may each also take the form of a single slab 17, as shown in Fig. 5 of the drawings, or the size of the oven may be increased by the use in each of the vertical 55 walls of a second slab 18, superposed upon

the slab 17, as shown in Figs. 1, 2 and 3. All of the wall members are chambered, as at 19, and this chamber is most desirably filled with a non-conducting packing, such, for example, as mineral wool.

60 In assembling the parts of the casing the lower edges of the side wall sections rest upon the margins of the floor slab 11, the roof or cover slab is laid upon the top edges of the side and end wall members, and the joints thus formed are bound with angle irons, as 20 (Fig. 4). Preferably those angle irons 20 which cover the joints about the floor slab 11, are connected at their ends by brackets 21, which provide legs for the 65 structure adapted to rest on the floor. An open rectangular frame is thus produced for receiving the floor slab 11 and the lower edges of the vertical wall members.

70 The vertical walls 13, 14, 15, 16, and cover 75 12 are preferably bolted together. As shown, horizontal tie-rods 22, which extend through the structure from end to end preferably within the chambers 19 of the side walls 15, 16, and through the vertical margins of the end walls 13, 14, bind the vertical angle irons 20 at each side of the structure together for this purpose. Similarly, those angle irons 20 which surround the cover slab 12 are secured in place by means of bolts 23, 80 which extend upwardly through the margins of the cover slab. Preferably the bolts 22 are secured at their lower ends within the chambers 19 of the side walls 15, 16, as by being attached by rivets 24 to the inner face 85 of the outer shell of the side wall members.

90 The oven illustrated in the drawings is of that form wherein gases from the fire which supplies heat for the baking operation are confined within flues and are not permitted to come in contact with the material to be baked. As shown, the chamber of the structure is divided into compartments, as 25, 26, 27 and 28, by a plurality of horizontal partitions or shelves 29, 30, 31, arranged at different levels. A fire-box, generally designated 32, is most conveniently located within the lowest compartment 25, and the partitions 29, 30 and 31, serve the purpose of shelves for receiving the material to be 95 baked.

100 The fire-box 32 is preferably of an inclosed form and is supported by a metal base frame 33, which rests upon the floor slab 11, the space 34 inclosed by the frame 105 110

constituting the ash-pit of the fire-box. Grate bars 35 carried by the frame 33, cover the ash-pit 34, and the fire-box proper takes the form of a tile-lined metal trough 36, 5 mounted on the frame 33 and covered by an arch-shaped tile 37. Most desirably the shelf 29 is heated by radiation from the fire-box 32 and by contact with its under side of the air confined within the compartment 25 about the fire-box. The higher shelves, as 30 and 31, on the other hand, are preferably chambered, as at 38, 39, and gases from the fire-box are delivered to the chambers of these shelves.

15 As shown, the shelves 29, 30 and 31 are of less width than the chamber of the casing 10, thereby providing for the passage of air from the compartment 25 about the fire-box 32 into the baking compartments 26, 27 20 and 28, as at 85 (Fig. 4). For supporting the shelves a plurality of transverse T-irons 40 are applied to the upper side of each, the ends, as 41, of certain of the T-irons being extended beyond the margins of the shelves 25 where they rest upon ledges, as 42, 43, formed upon the inside face of the side wall members of the structure. As shown, the ledges 42 are constructed from angle plates 44. These angle plates have one leaf se- 30 cured to the inside face of the outer shell of the lower sections 17 of the vertical wall members, as by means of rivets 45, and have the other leaf projecting horizontally through the inner shell of these side wall 35 sections, as most clearly shown in Fig. 3 of the drawings. In addition to providing the shelf-supporting ledges 42, these angle plates 44 serve the further functions of uniting the inner and outer shells of the 40 vertical wall sections 17 and of supporting the packing material 46 with which the chambers 19 of these wall sections are filled. The structure may be still further strengthened by securing one of the tie-rods 22 to 45 the horizontal leaf of each of the angle plates 44, at intervals throughout its length within the chamber 19 of the corresponding wall section, as by means of rivets 47 (Fig. 4).

50 The shelf-supporting ledges 43 most conveniently take the form of flanges formed upon the inner faces of the lower sections 17 of the side wall members 15, 16, adjacent their top edges. These flanges, and a similar 55 flange 86 formed on the back wall 14 (Fig. 2), serve for supporting an inner cover member 58, having marginal flanges 60, when the cover slab 12 is applied directly upon the top of the lower wall sections 17, as in Fig. 60 5 of the drawings. For supporting a similar cover member 87 when the oven is constructed as in Figs. 1 to 4 of the drawings, flanges 48 are provided upon the inner faces of the upper sections 18 of each of the side 65 wall members 15, 16, and back member 14,

adjacent the top edges of these sections. Most desirably each of the baking shelves, as 29, 30 and 31, is covered with tile 49, these tile being conveniently fitted into the spaces between the T-irons 40, as most 70 clearly shown in Fig. 2.

75 Preferably the chambers 38 and 39 of the shelves 30 and 31, are divided midway of the length of the shelves by vertical partitions, as 50, which extend from side to side of the chambers. To permit of these chambers being cleaned from one end of the shelf, these partitions are preferably pivotally supported in such a way that they may be 80 swung in a horizontal plane, as by being mounted upon a vertical pivot 51 provided at the center of the shelf.

Receiving and discharge flue heads, designated 52 and 53, respectively, communicating with the chambers 38, 39, of the shelves 85 30 and 31 at each side of the partitions 50, are provided at opposite sides of the shelves. As shown, the receiving flue heads 52 are downwardly-directed, and the discharge flue heads 53 are upwardly-directed, the receiving 90 and discharge flue heads at the two sides of the partition 50 of each shelf being at opposite sides of the shelf, respectively. As shown, flues 54 and 55, leading out of the chamber of the fire-box 32 at opposite sides 95 and extending up along the inside walls of the structure through the spaces 85 at the margins of the shelf 29, deliver to the receiving flue-heads 52 of the shelf 30. In the structure disclosed in Figs. 1, 2, 3 and 4 100 of the drawings, flue pipes 56 and 57, located adjacent opposite sides of the structure and at either side of the plane of the partitions 50, connect the discharge flue-heads 53 of the shelf 30 with the receiving 105 flue-heads 52 of the shelf 31.

110 The inner cover members 58, 87, are preferably chambered, and these chambers each constitute a receiving flue communicating with a stack 59. In the arrangement illustrated in Figs. 1 to 4 of the drawings embodying the cover member 87, flue pipes 61 and 62 lead from the discharge flue-heads 53 of the shelf 31 to the cover chamber. In the arrangement illustrated in Fig. 5 of the 115 drawings, flues pipes 63, 64, lead directly from the discharge flue-heads 53 of the shelf 30 to the cover chamber 58. In both cases furnace gases are delivered to the flue chamber of the cover members from opposite 120 sides and from points adjacent each end of the oven structure. The stack 59 is preferably connected to the top of the flue chamber over the cover member adjacent its center, and leads upwardly through the 125 cover slab 12.

Access to the several parts of the oven is preferably had through door openings in the front wall 13 of the structure. To this end doors 65, 66, leading into the chamber 130

of the fire-box 32 above and below the grate-bars 35, respectively, are preferably provided, and door openings 67 also lead through the front wall 13 to each of the baking compartments, as 26, 27, 28. Each of the openings 67 is normally closed by a door comprising a swinging leaf 68, covering the upper portion of the opening, and a vertically sliding leaf 69 covering the lower portion of the opening. As shown, a horizontal crank shaft 70 extends across the upper edge of each of the door openings 67, and to this crank shaft the swinging leaf 68 of the door is rigidly secured. Crank-arms 71 are applied to the crank shaft 70 at each side of the door opening. Preferably these crank-arms project radially from the crank shaft away from the swinging leaf 68 carried thereby, and the free ends of the crank shafts are connected by links 72 to the vertical sliding leaf 69 of the door. Preferably the weight of the swinging leaf 68 is sufficient to raise the corresponding sliding leaf 69 and thereby normally maintain the parts of the door in the closed position. Both parts of the door may, however, be simultaneously opened by pressure applied to the sliding leaf 69. To this end the upper edge of the sliding leaf is provided with a flange 73, which serves as a rest for the tool, not shown, employed for introducing or removing articles from the corresponding oven compartment.

Provision is also made for cleaning the flue chambers 38, 39 and 58, through the front wall 13 of the structure. To this end each of these flue chambers and the front wall 13 are provided with registering apertures 74, 75. These apertures are normally closed by a push cover 76 applied to the outer end of the aperture 75 of the front wall.

Most desirably the joints between the several members of the wall of the structure are of a form adapted to prevent leakage of air therethrough. The form of joint employed at the corners of the structure is most clearly illustrated in Figs. 2, 3 and 4 of the drawings. In each of the instances illustrated in these figures one of the members to be connected, as the end wall 13 (Fig. 4) has a mitered edge 77 and a flange 78 projecting beyond the mitered edge. The inner edge of the member to be connected thereto, as the side wall member 16, is chamfered, as at 79, to conform to the miter 77, and an inwardly-directed flange 80 extends across the face of the member at the base of the chamfered portion. When the parts are assembled, the unchamfered portion of the marginal edge of the side member bears against the flange 78 of the end member, and the flange 80 of the side member bears against the inside face of the end member. A wide bearing surface between the connected members is thus provided, and if this be packed,

as by means of a gasket 81 of asbestos paper, leakage of air is prevented. At those joints where connecting bolts, as 22, 23, are employed, the bolt extends through an aperture 82 in the flange 78. The top edge of the lower section 17 of each of the side and end wall members 13, 14, 15, 16, is chamfered, as at 83 (Figs. 2 and 5), to conform to the shape of the marginal edges of the cover slab 12, in order that the cover slab may be applied directly thereto, as in Fig. 5. In order, however, that a tight joint may be made between the lower sections 17 of the wall members and the superposed sections 18 illustrated in Figs. 1, 2 and 3, the bottom edges 84 of the superposed sections are made of a form complementary to the form of the top edge provided for the lower sections 17. It will thus be seen that the cover slab 12 may be applied interchangeably either to the top edge of the lower sections 17 of the wall members, or to the top edge of the sections 18 superposed thereon, and that in the latter arrangement an additional baking compartment 28 is provided in the oven.

Means are preferably provided for preventing overheating of the shelf 29. As shown, this shelf is chambered, as at 90 (Figs. 2, 3 and 5), and the front wall of the chamber is provided with apertures 91 which register with openings 94 in the front wall 13, controlled by dampers 92. The chamber 90 of the shelf 29 communicates with a flue of the furnace, as with the chamber of the shelf 30, through a flue 93 at the rear of the structure. If now the dampers 92 be opened air will be drawn from outside of the oven structure through the chamber 90 to the flue 93, thus cooling the shelf 29.

I claim as my invention—

1. In combination, a chambered wall for a baking compartment, a partition transverse to the plane of the wall dividing the chamber from end to end, a furnace flue leading into the chamber at each side of the partition, the openings of such flues into the chamber being at opposite ends of the wall, respectively, and a flue leading out of the chamber at each side of the partition, the opening from the chamber into each of said last-named flues being located at that end of the wall remote from the furnace flue opening at the same side of the partition.

2. In a bake oven, in combination, a baking compartment having a chambered floor and roof, a vertical partition dividing the floor chamber from side to side of the compartment, a furnace flue leading into the floor chamber at each side of the partition, the openings of such flues into the chamber being at opposite sides of the compartment, respectively, and a flue leading from the floor chamber at each side of the partition to the roof chamber, each of said last-named flues being located at that side of the com-

partment remote from the furnace flue delivering to the floor chamber at the same side of the partition.

3. In a bake oven, in combination, a baking compartment having a chambered floor and roof, vertical partitions extending from side to side of the compartment dividing the floor and roof chambers, respectively, a furnace flue leading into the floor chamber at each side of the partition therein, the openings of such flues into the chamber being at opposite sides of the compartment, respectively, and flues located at opposite sides of the partitions leading from the floor chamber to the roof chamber, each of said last-named flues being located at that side of the compartment remote from the furnace flue delivering to the floor chamber at the same side of the partition therein.

20 4. In combination, a chambered floor for baking compartments having a cleanout opening in an end wall of its chamber, a horizontally-swinging vertical partition normally dividing the floor chamber from side to side, and a furnace flue delivering to the floor chamber at each side of the partition.

5. In combination, a chambered floor for baking compartments having a clean-out opening in an end wall of its chamber, a horizontally-swinging vertical partition pivotally mounted at the center of the floor chamber and normally dividing the said chamber from side to side, and a furnace flue delivering to the floor chamber at each side of the partition.

35 6. In a door for bake ovens, in combination, a rotatable crank-shaft extending along one side of the door opening, a swinging leaf carried by the crank-shaft and normally covering a part of the door opening adjacent the crank-shaft, a sliding leaf covering a part of the door opening remote from the crank-shaft, and a link connecting the last-named leaf with a crank of the shaft.

45 7. In a door for bake ovens, in combination, a horizontal shaft extending along the top edge of the door opening, an inwardly-swinging leaf normally covering the higher portion of the door opening carried by the 50 crank-shaft, a vertically-sliding leaf mount-

ed in front of the swinging leaf and normally covering the lower portion of the door opening, crank-arms mounted on the ends of the crank shaft extending away from the swinging leaf, and links located at the sides 55 of the door opening connecting the vertically-sliding leaf with the crank-arms.

8. A bake oven comprising, in combination, a chambered casing having a removable double cover and side walls composed of 60 upper and lower sections, shelves arranged horizontally within the chamber of the casing and dividing the same into compartments, and a plurality of shelf-supporting ledges formed on the inside walls of the casing, one of such ledges being located adjacent the upper margin of the lower section of the side walls and being adapted to interchangeably receive one of the shelves and the inside member of the cover, the top edge of 65 the lower section of the side walls being adapted to receive either the lower edge of a superposed side wall section or the margins of the outer cover member.

9. A bake oven comprising, in combination, a chambered casing having a removable cover and side walls composed of upper and lower sections, the top edge of the lower one of the side wall sections being adapted to receive either the lower edge of the superposed 80 side wall section or the margins of the cover.

10. A bake oven comprising, in combination, a rectangular chambered structure having wall slabs joined at the corners of the structure, one of the wall slabs having a 85 mitered edge and a flange projecting beyond the miter, the edge of an adjacent wall slab being engaged with the said flange and being chamfered to engage the mitered edge of the first slab, an inwardly-directed flange 90 formed on the second-named slab at the base of its chamfered edge to bear against the inside face of the first slab and a clamping bolt projecting from the edge of the second-named slab and through the flange of the 95 first-named slab.

JOHN FAULDS.
